PRESSURE DEVICE FOR THE FLINTS OF
LIGHTERSLeon Bolle, Geneva, Switzerland, assignor to La
Nationale S. A., Geneva, Switzerland, a corpo-
ration of SwitzerlandApplication June 14, 1939, Serial No. 279,224
In Switzerland July 9, 1938

7 Claims. (Cl. 67—7.1)

In pyrophoric lighters known up to the present time, the pyrophoric flint is generally pressed against the friction wheel by a spring. The said spring expands in proportion to the wear of the flint and when it is desired to obtain a sufficient pressure until the flint has been used up completely, it is necessary either to provide means for adjusting this pressure or to use a very long spring of which the pressure is only slightly modified as a result of the shortening of the flint. But in order to mount a long spring in a lighter, it is frequently necessary to cause it to pass through the tank of the lighter whereby the capacity of the latter is reduced. When on the contrary it is desired to place the spring horizontally above the tank the lighter must be made of a width which is at least equal to the length of the compressed spring.

The present invention enables these disadvantages to be eliminated and in particular to mount the device which ensures the pressing up of the flint entirely outside the tank, while the lighter is still of slender shape.

In the device forming the subject of the present invention, the spring is simply divided into a number of sections which are connected together mechanically, the two extreme sections each contact with one end, one against the pyrophoric flint and the other against a bearing point, in such a manner that as a whole they present the same elasticity as a single spring of the same total length as all the sections, this elasticity being capable, without adjustment, of the effective operation of the lighter until the flint has been worn completely.

A form of construction of the subject of the present invention is shown in sectional elevation in the accompanying drawing.

The fuel container 1 carries on its upper face a friction wheel 2 mounted on a shaft 3 driven by a knob 4 projecting to the outside of the container. The support 5 for the shaft 3 is provided with an extension 6 in which is formed a tubular socket 7 and on the end of the shaft is pivotally mounted a member 8 provided with a tubular seating adapted to receive a pyrophoric flint 9. This member may be brought opposite another member 10 also provided with a tubular seating in which slides a hollow follower 11 provided with a projection 12 which passes through a longitudinal slot in the member 10 and enables the piston to be actuated manually when fitting the flint 9 in position. As will be seen from the drawing the follower 11 enters the socket con-

taining the flint 9 and thus holds the member 8 in position.

The members 6 and 10 do not extend up to the edge of the upper face of the container 1 opposite that carrying the friction wheel 2, but leave at this point an open space 13 in which is mounted a double armed lever 14 pivotally mounted at its mid-portion at 13 and of which the ends are respectively located opposite the socket 7 and the follower 11. The double armed lever is provided at its lower end 16 with an opening in which is mounted the end of a guide rod 17 for a spring section 18. This rod is retained in position by a pin 19 against which there bears one end of the spring 18 of which the other end is located in the tubular socket 7. The other end 20 of the lever 14 is provided with a small fixed projection which enters one end of a spring 21 located in the follower 11.

22 indicates the cover of the lighter and is hinged at 23.

The operation of this device will be readily understood. The two spring sections 18 and 21, arranged parallel to one another and connected mechanically at one of their ends by means of the lever 14, act on the flint 9 in the same manner as a spring formed in one piece of greater length, having an expansion and a force sufficient to ensure the satisfactory operation of the lighter. As will be seen from this form of construction the thrust of the spring section 18 on its bearing point takes place in the same direction as that of the section 21 on the flint 9.

The piston 11 passes into the member 8 in proportion to the wear of the flint 9 against the friction wheel 2. For inserting a new flint the follower 11 is withdrawn rearwardly against the action of the springs 18, 21 by means of the knob 12 until the member 8 has been disengaged and can pivot laterally.

It will be obvious that the invention may be carried out in a manner different from that shown in the drawing.

The guide rod 17 may in some cases be omitted or a similar guide may be provided on the end 20 of the lever 14. The spring may be divided into more than two sections in such a manner as to make it of much greater length and the various sections need not necessarily be located parallel to one another.

This arrangement has the considerable advantage of enabling spring sections to be mounted in lighters of small dimensions at a point where the construction of the lighter leaves the necessary space.

I claim:

1. A device for pressing a flint against a friction wheel comprising in combination a shaft, an operating knob mounted on said shaft, a friction wheel mounted on said shaft, a guide member pivotally mounted on said shaft, a flint located in said guide member, a second guide member on said shaft, a third guide member mounted adjacent the ends of said first two guide members, a hollow follower mounted in said third guide member, said follower engaging the first guide member and being adapted to bear against said flint, a projection on said follower for retracting the same, a spring located in said hollow follower, a spring located in said second guide member, said springs extending parallel to one another, a guide rod located in said second spring, a pivotally mounted lever, one end of said lever being engaged by said guide rod and the other end of said lever engaging said first mentioned spring.

2. In a lighter, the combination with a flint wheel, a flint, a guide for the flint, of means for pressing the flint in the guide toward the wheel, said means comprising a plurality of normally compressed springs arranged in spaced parallel relation and having one pair of related ends abutting a lever pivoted between its ends, said springs also having their other pair of ends respectively abutting the flint in the guide and a fixed abutment.

3. In a lighter, the combination with a flint wheel, a flint, and a guide for the flint, of means for pressing the flint in the guide toward the wheel, said means comprising a tubular follower provided at one end with a wall whose outer side abuts against the flint and whose inner side constitutes a spring abutment face, a lever having an intermediate pivot and the opposite ends thereof constituting spring abutments, a spring confined in the tubular follower between the abutment face thereof and one abutment of the lever, a second spring having one end engaging a fixed abutment and its opposite end engaging the other abutment of said lever.

4. In a lighter, the combination with a flint wheel, a flint, a tubular flint guide mounted for pivotal movement co-axially with the flint wheel, a fixed support, a tubular follower slidable in said fixed support and having one end adapted

to register with the tubular flint guide, means on the tubular follower for manually sliding the same to disengage the tubular flint guide, a first compressed spring in the tubular follower for advancing the same toward the flint, and auxiliary means including a second compressed spring for exerting force against the rear of the first named spring for advancing the same toward the flint to compensate for said loss of compression in the first named spring as it expands due to wear of the flint, said second spring being mounted to exert its force along a line different from the line along which said first spring exerts force, said auxiliary means further comprising a serial connection between said springs which positively adds their respective resilient forces serially and colinearly against said flint.

5. In a lighter, the combination with a flint wheel, a flint, a guide for the flint and a fixed spring abutment, of means for pressing the flint in the guide toward the wheel, said means comprising a set of normally compressed springs arranged in spaced parallel relation and having their inner ends engaging an abutment pivoted between its ends, said springs having their outer ends respectively abutting the flint in the guide and said fixed spring abutment.

6. In a pyrophoric lighter including a flint wheel and a flint, means for urging the flint against the flint wheel, comprising, a plurality of normally compressed coil springs one of which engages the flint, said springs arranged in parallel side by side relation, and means at the adjacent ends of each spring for causing them to transmit their combined energies to the flint thereby automatically to feed the flint to the wheel until it is completely worn away.

7. In a pyrophoric lighter, a flint, a flint wheel, and elastic means for urging said flint against said flint wheel comprising a pair of helical springs mounted with their axes parallel and spaced apart, a first one of said springs being mounted to bear on one of its ends against said flint, an abutment against which the second of said springs bears on one of its ends, said elastic means further comprising a lever connection connecting the free ends of said springs and adapted to additively apply the combined forces of said springs serially colinearly against said flint.
